UNITED STATES PATENT OFFICE.

ERNEST YEOMAN ROBINSON, OF WITHTINGTON, MANCHESTER, ENGLAND, ASSIGNEE
TO METROPOLITAN-VICKERS ELECTRICAL COMPANY LIMITED, OF LONDON, ENGLAND, A BRITISH JOINT-STOCK COMPANY.

VACUUM ELECTRIC TUBE.

Application filed June 2, 1924, Serial No. 717,328, and in Great Britain June 14, 1923.

This invention relates to vacuum electric tubes containing cathodes which are heated for example by a thermionic bombardment or by radiation from a heated auxiliary member such as a filament or by high frequency electromagnetic induction and which are of sheet material in flat or tubular form. The object of the invention is an improved method of supporting such cathodes and 10 leading in the current thereto.

According to this invention it is arranged that one or more sheets or tubes comprising the cathode are supported by a plurality of supports such for example as stems and 15 moreover are preferably supported on a plurality of sides. In this manner the cathode may be rigidly fixed with respect to other electrodes of the device.

Furthermore, the cathode supports whilst 20 capable of movement in a longitudinal direction are fixed in other directions so that expansion thereof is permitted.

The supporting stems may be employed 25 as electrical leads to the cathode.

This method of supporting and constructing the cathode has several advantages. Firstly, the cathode or cathode portions are supported more rigidly and the electrodes may therefore be given a small separation; 30 secondly, where the cathode is of the type described in the specification of my copending application Serial No. 653,544 filed 24th July 1923 the cathode portions may be spaced from each other by means of spacing pieces 35 inserted between the supporting stems and either fixed thereto or arranged to be in sliding contact therewith; thirdly the plurality of leading-in wires to the cathode and the spacing of these round the cathode edges results in a more uniform distribution of current in the cathode sheet or tube and thus 40 promotes more uniform heating; fourthly, it becomes necessary when cathodes of large emission surface are employed to use a plurality of leads connected to the cathode to prevent overheating of the lead-in wires.

In the accompanying drawing:—

Fig. 1 represents a section taken axially or longitudinally through a cathode structure embodying the present invention; and 50

Fig. 2 is a detail perspective view of one of the members of the cathode structure shown in Fig. 1.

Referring to Fig. 1, the cathode structure

therein illustrated is adapted for use, for example, in a tube of the type set forth in the specification of my copending application Serial No. 603,715 filed 27th November, 1922.

In the construction shown in Figs. 1 and 2 the cathode is of the type described in my copending application Serial No. 653,544 hereinbefore referred to, it comprising an outer tube 3, an inner tube 15 and a starting filament 16. The two tubes 3 and 15 are provided with perforations 87 formed near the ends of the tubes. The two tubes 3 and 15 are mounted with respect to and insulated from one another by means of steatite bushes 88 and 89. Each brush comprises two cylindrical portions of different diameter, as clearly shown. The inner tube 15 fits upon the smaller portions of the bushes and is attached thereto by means of set screws 90. The outer tube 3 is of greater length than the inner tube 15 and is attached to the upper bush 88 by means of set screws 91 whilst the lower end of the tube slides freely upon the larger portion of the bush 89. The upper end 92 of the outer tube 3 extends beyond the bush 88 and is connected by means of the arms 45 to a clamp or the like by means of which it can be secured, for example, to a re-entrant portion of the tube envelope. The arms 45 may constitute the lead-in conductor for the outer tube 3. A lead-in conductor 93 passes through the upper bush 88 and is connected by means of a nickel or other conductor 94 to one of the circumferentially spaced arms or strips formed by the portions 95 of the tube intervening between the longitudinal slots or perforations 87. Such arms or strips 95, it will be appreciated, constitute a plurality of supports at both ends of the cathode tubes and they also constitute a plurality of lead-in conductors for said tubes at the upper end thereof as these strips are all connected electrically by the upper terminals of the respective tubes. The starting filament 16 is connected to the lead-in conductors 23 and 24 which pass through the upper bush 88. The bight of the filament 16 is engaged by a hook 31 attached to a rod 96 which carries the shield 4 and passes through the lower bush 89 being retained therein by two abutments 97 welded to the rod.

The cathode tubes 3 and 15 are formed of metal having a comparatively low melting

point. For example they may consist of steel, iron, nickel or molybdenum and are coated on their active surfaces, that is to say on the portions which are disposed between the perforations 87, with a substance such as a mixture of barium and strontium oxides for facilitating emission of electrons. Such coating may be applied in any suitable manner such for example as that set forth in the specification of my copending application Serial No. 715,653 filed May 24, 1924. Since the tubes are not coated at their ends these portions will remain inactive and therefore will effectively confine the space current to the interelectrode space. The cathode may be mounted within an anode. The starting cathode 16 may be a tungsten filament or an oxide coated filament and adapted to heat the inner tube 15 by electronic bombardment or heat radiation as the case may be.

Although one specific construction has been illustrated and described it will be understood that the invention is not limited to same since various modifications may be made without departing from the scope of the invention.

I claim as my invention:—

1. Cathode means for a vacuum electric tube comprising a sheet metal cathode, an auxiliary member for heating said sheet metal cathode by transference of energy thereto, a plurality of parallel-connected strips formed integrally with said sheet metal cathode at a plurality of distributed points at both ends thereof, and a single terminal conductor connected to said strips.

2. Cathode means for a vacuum electric tube comprising a sheet metal cathode adapted to be heated by the transference of energy to it, for causing it to emit electrons, and having a plurality of strips formed integrally with it at a plurality of distributed points, and a supporting member, said strips being carried movably upon said supporting member so that the cathode can expand without distortion thereof.

3. Cathode means for a vacuum electric tube comprising a sheet metal cathode adapted to be heated by the transference of energy to it, for causing it to emit electrons, and having a plurality of strips formed integrally with it at a plurality of distributed points, and a supporting member, said strips being slidable upon said supporting member to permit expansion of the cathode without distortion thereof.

4. Cathode means for a vacuum electric tube comprising a sheet metal cathode having an electron-emitting portion and a plurality of strips integral with said electron-emitting portion and extending therefrom at a plurality of distributed points.

5. Cathode means for a vacuum electric tube comprising a sheet metal cathode hav-

ing an electron-emitting portion and, at each end thereof, a plurality of strips integral with said electron-emitting portion and extending therefrom at a plurality of distributed points.

6. Cathode means for a vacuum electric tube comprising a sheet metal cathode having an electron-emitting portion and a plurality of strips formed integrally with said electron-emitting portion and extending therefrom at a plurality of distributed points, and a terminal conductor to which said strips are electrically connected in parallel.

7. Cathode means for a vacuum electric tube comprising a sheet metal cathode having an electron-emitting portion and, at each end thereof, a plurality of strips integral with said electron-emitting portion and extending therefrom at a plurality of distributed points, and a terminal conductor to which said strips are electrically connected in parallel.

8. Cathode means for a vacuum electric tube comprising a tubular sheet metal cathode having, at one end at least, a plurality of strips integral therewith and terminating in a single terminal member.

9. Cathode means for a vacuum electric tube comprising a tubular sheet metal cathode having, at one end at least, a plurality of cylindrically disposed strips formed integrally therewith and terminating in a member which has the form of a cylindrical collar.

10. Cathode means for a vacuum electric tube comprising a tubular sheet metal cathode having, at one end at least, a plurality of cylindrically disposed strips formed integrally therewith and terminating in a member having the form of a cylindrical collar, and an internally disposed auxiliary member for heating said cathode by transference of energy thereto.

11. Cathode means for a vacuum electric tube comprising a tubular sheet metal cathode having, at one end at least, a plurality of cylindrically disposed strips formed integrally therewith and terminating in a member which has the form of a cylindrical collar, and an internally disposed auxiliary member for heating said cathode by transference of energy thereto, said auxiliary member embodying a tubular sheet metal element having, at one end at least, a plurality of cylindrically disposed strips formed integrally therewith and terminating in a member which has the form of a cylindrical collar.

12. Cathode means for a vacuum electric tube comprising a cylindrical sheet metal cathode, an internally disposed cylindrical auxiliary member for heating said cathode by transference of energy thereto, said cathode and auxiliary member being slotted

longitudinally adjacent to their ends to form multiple strips integral therewith, and at least one bush of insulating and heat resisting material provided with two cylindrical portions of different diameters which portions respectively receive the ends of said cathode and said auxiliary member and support them relative to one another.

13. Cathode means for a vacuum electric tube comprising a cylindrical sheet metal cathode, an internally disposed cylindrical auxiliary member for heating said cathode by transference of energy thereto, the cathode and auxiliary member having circumferentially spaced strips formed integrally

therewith and terminating in cylindrical collars, a bush of insulating and heat resisting material provided with cylindrical portions of different diameters which respectively receive the cylindrical collars of said cathode and said auxiliary member and support them relatively to one another, and an element within said auxiliary member which is capable of being heated by passage of an electric current through it and is supported by said bush.

In testimony whereof I have subscribed my name this ninth day of May, 1924.

ERNEST YEOMAN ROBINSON.
